UNITED STATES PATENT OFFICE.

SETH HART AND ROBERT I. EUSTIS, OF LOS ANGELES, CALIFORNIA.

AIRPLANE.

Application filed May 17, 1920. Serial No. 381,867.

To all whom it may concern:

Be it known that we, SETH HART and ROBERT I. EUSTIS, citizens of the United States, residing at Los Angeles, county of Los Angeles, State of California, have invented certain new and useful Improvements in Airplanes, of which the following is a specification.

This invention relates to improvements in airplanes. It has more particularly to do with the control of the propelling means.

The objects of the invention are:

First, to provide an effectively controlled propeller whereby the angle of the propeller blades can be controlled and the propeller regulated in its action while the machine is flying.

Second, to provide such an adjustable propeller in which the blades can be reversed by the pilot.

Third, to provide direct connection means from the cockpit of an airplane to control the propeller and regulate the angle of the blades, either for varying the action of the propeller or for reversing the same.

Fourth, to provide improved control means for an airplane in lighting or landing.

Further objects and objects relating to details and economies of construction and operation will definitely appear from the detailed description to follow.

We accomplish the objects of our invention by the devices and means described in the following specification. The invention is clearly defined and pointed out in the claims.

A structure which is a preferred embodiment of our invention is fully illustrated in the accompanying drawing, forming a part of this specification, in which:

Fig. I is a detail perspective view of our invention adapted and applied to a Curtis JN4H airplane.

Fig. II is an enlarged detail plan view of the front end of the engine, the propeller hub and the connecting means for our improvements, a portion of the propeller blades being broken away.

Fig. III is an enlarged detail transverse elevation view, partially in section, on line 3-3 of Figs. II and VII, showing details of the adjusting means for varying the angle of the propeller blades while the machine is in flight.

Fig. IV is an enlarged detail transverse

sectional view taken on line 4-4 of Figs. II and III, showing details of the yoke connection, the outer portion of the propeller blades being broken away.

Fig. V is an enlarged elevation view of the control lever and segment and of the throttle control as it would appear from the inside of the cockpit.

Fig. VI is an enlarged detail view of the improved latch and notched segment portion whereby very fine adjustment is secured.

Fig. VII is a detail longitudinal sectional view through the hub sleeve and inner end of the propeller blade, showing a sleeve and thrust bearing for a propeller blade, taken on line 7-7 of Figs. III and IV.

Fig. VIII is an enlarged detail view, partially in section, of the yielding spring device in the connection rod to the throttle control, taken on line 8-8 of Fig. V.

In the drawing all the sectional views are taken looking in the direction of the little arrows at the ends of the section lines and similar numerals of reference refer to similar parts throughout the several views.

Considering the numbered parts of the drawing, the numeral 1 indicates generally the improved propeller means, 2 is the fuselage of an airplane, 3 is the radiator, 4 is the front end of the engine, 5 is the hub of the propeller secured to the propeller shaft 5'. 6, 6 are the propeller blade sleeves preferably made integral with the hub 5. The propeller blades 7 are of the usual construction, being somewhat modified to make them reversible. The inner ends of the propeller blades are supported in thrust ball or roller bearings 8 and 9, as seen in Fig. VII, as it is desirable to minimize the friction to facilitate the manipulation. Friction is occasioned by the heavy centrifugal pull on the blades. A vertical pin 10 is inserted through the shank of each propeller blade and when in the vertical position the propeller blades are at neutral.

We show the details of the right hand propeller blade, which of course is identical with the other blade when it is swung to the same position, as the two parts are precisely symmetrical. Therefore the description of one of these devices is sufficient for both.

The pin 10 is connected by a link 11 through its pivot 12 to the yoke or ring bearing 13 having a bracket 14 thereon to which the link 11 is pivoted at 15. A yoke

16 is secured to the inner end of the hub 5 and is disposed transversely to the propeller hub sleeves. Pins 17 extend therefrom to bosses 18 above and below the center of the hub and the sliding yoke or ring 13 is slidably disposed on these pins or rods 17 so that the same may be moved readily back and forth thereon. The bearing yoke 20 embraces the revolving ring 13, there being a suitable thrust ball bearing between the same, not necessary to be shown here, as our invention does not pertain to the detail of the bearing.

To this bearing yoke is secured a pair of pins 21 (see Figs. II, III and IV) which are carried by the brackets 22 secured to the forward end 4 of the engine. These are provided with suitable ways 33 within which the pins 21 are adjusted. The adjusting is effected by a rock shaft 24 carried by the bracket 22 disposed transversely of the propeller shaft beneath the yoke 20. Upwardly extending arms 25 are slotted at 26 to receive the pins 27 on the opposite ends of the yoke 20. Arms 28 extend down from this rock shaft.

Each rock shaft arm 28 is operated by a control lever 29 in the cockpit, the same having downwardly depending arm 30 connected by the control rod 31 to the arm 28 (see Figs. III and V). The control lever 29 is pivoted to the segment plate 34 on the fulcrum 32. The segment 34 is secured to a frame piece 35 of the fuselage. The segment is provided with internal gear teeth 36 which are engaged by a latch 37 having double teeth 38, 38 spaced to engage one notch and ride upon a tooth at the opposite side, making the adjustment a half of a tooth. The latch is controlled by the rod 39 from the push button 40 at the top of the control lever 29 (see Fig. V).

Because of the danger of speeding an airplane engine, there is associated with the reverse lever in the cockpit a control for the throttle when reversing the propeller. This consists of a lever 41 fulcrumed at 42 on the control segment and connected at 44 through the special rod 43 to the throttle control 45. The throttle control rod is divided and provided with extensible spring means which come into play when the propeller control is off the neutral. A compression coil spring 46 engages a head 47 on the upper portion of the rod, and a sleeve 48 is carried by the lower portion of the rod, and has a cap retaining the spring in its operative position. The lengthening of the throttle control rod is thus permitted when the propeller control lever is off the neutral and is locked when the propeller is at neutral. The auxiliary lever 41 is disposed at the side of the propeller control lever 29 and is provided with a cam slot 50 which is engaged

by a roller 51, the cam being so shaped that the lever 41 throttles the engine when the lever 29 is moved to the neutral position, as will clearly appear from an inspection of Fig. V. It is important to throttle the engine at this point to facilitate the manipulation.

With this improved construction it is possible for the pilot of an airplane to manipulate and completely and effectively control the angle of the propeller blades. As the airplane ascends into higher atmosphere it is desirable to turn the blades to cause them to advance more strongly and thus most effectively advance the airplane. The blades revolve much more freely in the attenuated air of the higher altitudes.

This adjustment enables the full power of the engine to be utilized. This adjustment of the angle of the propeller blades is also of great advantage at the take off, as it enables the adjustment to be made precisely to the power of the engine and the most powerful result is attained.

The reversing feature of the propeller enables the aviator to substantially stop his plane in mid-air. This would be a matter of great advantage in combat, as it would give the pilot such control of his machine as to minimize the attack of an enemy.

However, this matter of the reverse of a propeller in the air is only of special consequence, whereas the proper reversing of the propeller in landing after every flight is of the very highest consequence, as it enables the machine to land safely and in a very short space. Machines have been landed and stopped upon the ground considerably within one hundred feet, depending upon the power of the engine and the relative weight of the plane, the landing space required for an airplane can be thus very greatly lessened, so that level space a few times the length of the machine is all that is necessary to effect a landing.

This landing is accomplished by the pilot when he approaches comparatively close to the ground, with his engine running at full speed, by quickly throwing the control lever clear over into reverse. This is possible here because he has direct connection and direct control and also has connection that prevents speeding of his engine while the reverse is being made. The direction of revolution is not changed. It is thus possible to put brakes upon the airplane when it is a little distance above the ground and it will drop immediately to the ground and the reversal of the propeller acts as a powerful brake, stopping the machine within a comparatively few feet. This is a matter of very great consequence in avoiding accidents in landing and also insuring landing within a limited area, and makes it practical to utilize small landing fields.

By use of our invention it will thus be observed that it is possible for the pilot of an airplane to completely and instantly regulate the action of the propeller and thereby the whole machine. This is a matter of importance in the take off. It is also a matter of high consequence when the machine reaches high altitudes where the air is attenuated. The reversal of the propeller by substantially the same means enables the pilot to completely control his flight, as it is not necessary to stop the engine to stop the advance, and he can also reverse, thus putting on brakes in mid-air, giving him complete control, which is desirable in combat or in emergency of any kind. Also, because the control is instantaneous and because it is feasible to reverse the propeller by almost instant action, greatly lessened landing areas are needed and greater safety is attained in the matter of landing. A small field can be availed of in an emergency.

We have provided simple and effective means which we desire to claim specifically herein, but it is also desired to claim the broad combination in an airplane of the devices and means that we have produced, as pointed out in the appended claims.

Having thus described our invention what we claim as new and desire to secure by Letters Patent is:

1. The combination of an airplane, a propeller shaft therefor, a propeller hub with lateral sleeves, adjustable propeller blades supported in the said sleeves, a yoke transverse to the said sleeves on the said propeller hub, supporting pins from the said yoke to the said hub parallel to the axis of said hub, an axially adjustable ring carried by said pins and revolute with said hub, pivoted link connections from the said ring to said adjustable propeller blade, one above and the other below the said sleeves, an adjustable bearing yoke carried by the engine and embracing said adjustable ring and constituting a bearing support therefor, ball thrust bearings between said adjustable yoke and ring, pins carried by said adjustable yoke and disposed parallel to the propeller shaft, brackets on the front end of the engine with bearing ways for said pins, a rock shaft carried by said brackets, arms on said rock shaft slotted to engage pins on the end of said adjustable yoke, an adjusting lever with lock segment in the cockpit of said airplane, connections therefrom to said rock shaft, all coacting substantially as described for the purpose specified.

being formed to actuate the throttle and to throttle the engine when the adjusting lever is at neutral, all coacting substantially as described for the purpose specified.

2. The combination of an airplane, a propeller shaft therefor, a propeller hub with lateral sleeves, adjustable propeller blades supported in the said sleeves, a yoke transverse to the said sleeves on the said propeller hub, supporting pins from the said yoke to the said hub parallel to the axis of said hub, an axially adjustable ring carried by said pins and revolute with said hub, pivoted link connections from the said ring to said adjustable propeller blade, one above and the other below the said sleeves, an adjustable bearing yoke carried by the engine and embracing said adjustable ring and constituting a bearing support therefor, ball thrust bearings between said adjustable yoke and ring, pins carried by said adjustable yoke and disposed parallel to the propeller shaft, brackets on the front end of the engine with bearing ways for said pins, a rock shaft carried by said brackets, arms on said rock shaft slotted to engage pins on the end of said adjustable yoke, an adjusting lever with lock segment in the cockpit of said airplane, connections therefrom to said rock shaft, all coacting substantially as described for the purpose specified.

3. The combination of an airplane, a propeller therefor with reversible propeller blades, a control lever in the cockpit of the airplane, connections from said control lever to said reversible blade, an auxiliary lever disposed in operative relation to said control lever, having a cam therein, a pin on the control lever operating on said cam, connections from the said auxiliary lever to the throttle of the engine, said cam being formed and disposed to automatically throttle the engine when the control lever is moved to neutral, coacting as specified.

4. The combination of an airplane, a propeller shaft therefor, a propeller hub with lateral sleeves, adjustable propeller blades supported in the said sleeves, a yoke transverse to the said sleeves on the said propeller hub, supporting pins from the said yoke to the said hub parallel to the axis of said hub, an axially adjustable ring carried by said pins and revolute with said hub, pivoted link connections from the said ring to said adjustable propeller blade, one above and the other below the said sleeves, an adjustable bearing yoke carried by the engine and embracing said adjustable ring and constituting a bearing support therefor, ball thrust bearings between said adjustable yoke and ring, pins carried by said adjustable yoke and disposed parallel to the propeller shaft, brackets on the front end of the engine with bearing ways for the throttle of the engine, the said cam

said pins, and means for adjusting said bearing yoke.

5. The combination of an airplane, a propeller shaft therefor, a propeller hub with lateral sleeves, adjustable propeller blades supported in the said sleeves, a yoke transverse to the said sleeves on the said propeller hub, supporting pins from the said yoke to the said hub parallel to the axis of said hub, an axially adjustable ring carried by said pins and revoluble with said hub, pivoted link connections from the said ring to said adjustable propeller blade, one above and the other below the said sleeves, an adjustable bearing yoke carried by the engine and embracing said adjustable ring and constituting a bearing support therefor, ball thrust bearings between said adjustable yoke and ring, and means for supporting and adjusting said bearing yoke.

6. The combination of an airplane, a propeller shaft therefor, a propeller hub with lateral sleeves, adjustable propeller blades supported in the said sleeves, a yoke transverse to the said sleeves on the said propeller hub, supporting pins from the said yoke to the said hub parallel to the axis of said hub, an axially adjustable ring carried by said pins and revoluble with said hub, pivoted link connections from the said ring to said adjustable propeller blade, one above and the other below the said sleeves, an adjustable bearing yoke carried by the engine and embracing said adjustable ring and constituting a bearing support therefor, pins carried by said adjustable yoke and disposed parallel to the propeller shaft, brackets on the front end of the engine with bearing ways for said pins, a rock shaft carried by said brackets, arms on said rock shaft slotted to engage pins on the end of said adjustable yoke, an adjusting lever with lock segment in the cockpit of said airplane, and connections therefrom to said rock-shaft.

7. The combination of an airplane, a propeller shaft therefor, a propeller hub with lateral sleeves, adjustable propeller blades supported in the said sleeves, a yoke transverse to the said sleeves on the said propeller hub, supporting pins from the said yoke to the said hub parallel to the axis of the said hub, an axially adjustable ring carried by said pins and revoluble with said hub, pivoted link connections from the

said ring to said adjustable propeller blade, one above and the other below the said sleeves, an adjustable bearing yoke carried by the engine and embracing said adjustable ring and constituting a bearing support therefor, and means for supporting and adjusting said bearing yoke.

8. The combination of an airplane, a propeller shaft therefor, a propeller hub with lateral sleeves, adjustable propeller blades supported in the said sleeves, an axially adjustable ring carried by said hub, pivoted link connections from the said ring to said adjustable propeller blade, one above and the other below the said sleeves, an adjustable bearing yoke carried by the engine and embracing said adjustable ring and constituting a bearing support therefor, pins carried by said adjustable yoke and disposed parallel to the propeller shaft, brackets on the front end of the engine with bearing ways for said pins, a rock shaft carried by said brackets, arms on said rock shaft slotted to engage pins on the end of said adjustable yoke, an adjusting lever with lock segment in the cockpit of said airplane, and connections therefrom to said rock-shaft.

9. The combination of an airplane, a propeller shaft therefor, a propeller hub with lateral sleeves, adjustable propeller blades supported in the said sleeves, an axially adjustable ring carried by said hub, pivoted link connections from the said ring to said adjustable propeller blade, one above and the other below the said sleeves, an adjustable bearing yoke carried by the engine and embracing said adjustable ring and constituting a bearing support therefor, pins carried by said adjustable yoke and disposed parallel to the propeller shaft, brackets on the front end of the engine with bearing ways for said pins, a rock shaft carried by said brackets, and arms on said rock shaft slotted to engage pins on the end of said adjustable yoke.

In witness whereof, we have hereunto set our hands and seals.

SETH HART. [L.S.]
ROBERT I. EUSTIS. [L.S.]
